GASEOUS ELECTRIC DISCHARGE LAMP
DEVICE

Willem Uyterhoeven and Cornelis Verburg, Eindhoven, Netherlands, assignors to General Electric Company, a corporation of New York

Application September 1, 1934, Serial No. 742,396
In Germany September 25, 1933

4 Claims. (Cl. 176—124)

The present invention relates to gaseous electric discharge lamp devices generally and more particularly the invention relates to illuminating systems comprising such devices.

- 5 Gaseous electric discharge lamp devices, the gaseous atmosphere of which consists of or comprises the vapor of difficultly vaporizable metals, that is metals having a vapor pressure of less than 1 mm. at a temperature of 200° C., such as 10 sodium, cadmium, magnesium, thallium and zinc, and in which the metal vapor is a light emitting element, are efficient light sources. The vapor in such devices does not reach an effective operating pressure for an appreciable time after 15 the start of such lamp devices since the device does not reach the temperature required for an effective vapor pressure until considerable time has elapsed after the starting period.

- The object of the invention is to provide means 20 to shorten the time required for vapor lamps of the above type to reach their operating temperature after the start of the device. Another object of the invention is to provide a circuit for such devices whereby the time required for the 25 device to reach its operating temperature and pressure is considerably reduced. A further object of the invention is to provide a simple lamp unit comprising a lamp device of the above type. A further object of the invention is to provide 30 an illuminating system comprising a gaseous electric discharge lamp device requiring an appreciable time after starting to attain its operating temperature and another gaseous electric discharge lamp device which attains its operating temperature a short time after starting 35 whereby the time required for said first named device to attain its operating temperature is substantially reduced. Still further objects and advantages attaching to the device and to its 40 use and operation will be apparent to those skilled in the art from the following particular description.

- In accordance with these objects the invention comprises a circuit having a vapor lamp 45 therein of the type requiring an appreciable time after the starting thereof to reach its operating temperature and to build up an effective vapor pressure and another gaseous electric discharge lamp device of the type which reaches 50 its operating temperature a short time after starting. The two lamp devices are connected in series during the operation thereof and means are provided in the circuit to short circuit the lamp device which reaches its operating 55 temperature quickly until the other of said devices

has reached its operating temperature. The device requiring an appreciable time to reach its operating temperature is thus considerably overloaded during the starting period thereof and quickly reaches its operating temperature. When 5 said last named device has reached its operating temperature the other of said devices is connected into the circuit in series therewith. Since the discharge device with the short heating time is short circuited during the starting period of the 10 other of said devices, the potential required to start the lamp devices in the circuit into operation is appreciably lower than is the case when both of said devices are started into operation simultaneously. On an alternating current supply 15 this lower potential results in an appreciably better performance factor.

In order to avoid the possibility of interrupting the discharge in the device first started when the second device is started into operation a 20 high impedance is connected in the circuit in parallel with the discharge device having a short heating time. This impedance consists of a high resistance, or, in the case of alternating current, the impedance consists of a resistance, choke 25 coil, or a condenser, when desired. A condenser is also useful in connection with the device having the short heating time as the starting thereof is facilitated thereby.

It is desirable to provide automatic means for 30 connecting into the circuit the device having the short heating time when the device containing the vapor of a metal difficult to vaporize has reached its operating temperature. If the two devices are mounted in adjacent positions light 35 rays from each lamp are commingled which improves the color of the light emitted by a lamp unit comprising such devices. Discharge devices having a gaseous atmosphere comprising metals which are difficult to vaporize are usually provided with a heat conservator to reduce the heat losses therefrom. An evacuated envelope enclosing the lamp device or a double walled jacket having the space between the walls thereof evacuated and in which the lamp device is mounted 40 are effective heat conservators. It is desirable to mount both lamp devices inside of the same conservator to form a lamp unit.

The invention will be readily understood by an inspection of the drawing accompanying and 50 forming part of this specification wherein an embodiment of the invention is shown schematically and from the following detailed description thereof.

Referring to the drawing the new and novel 55

circuit comprises a gaseous electric discharge lamp device 1 having electrodes which are electron emitting when heated and a gaseous filling comprising a fixed, starting gas, such as 5 neon, and the vapor of a difficultly vaporizable material, such as sodium. Said lamp device 1 is connected across the terminals 2 of an alternating current source and an auto-inductance 3 is connected in series with said lamp device 1. 10 A second gaseous electric discharge lamp device 4 having electrodes which are electron emitting when heated and a gaseous filling consisting of a rare gas, such as neon, is connected in series with said lamp device 1. A switch 5 is connected across the terminals of the lamp device 4 and short-circuits said lamp device 4 when closed. The movements of said switch 5 are controlled by a time delay, electro-magnetic relay, the coil 6 of which is connected in series with the lamp devices 1 and 4. A resistance 7 is connected in 15 parallel with said lamp device 4.

When current is applied to the above described circuit the switch 5 is closed which short circuits the lamp device 4. A strong current is thus applied to the lamp device 1 so that said lamp device 1 is rapidly heated to its operating temperature and the difficultly vaporizable material therein is quickly vaporized. The vapor pressure in the lamp device 1 is rapidly built up to 20 an effective operating pressure at which pressure the vapor emits light when excited by the passage of an electric discharge therethrough.

The relay 6 is so adjusted that as soon as the lamp device 1 has reached its operating temperature said relay 6 opens the switch 5 to connect the lamp device 4 in series with the lamp device 1. The lamp device 4 is thus started into operation and quickly reaches its operating temperature. The resistance 7, connected in parallel with the lamp device 4, prevents the interruption of the discharge in said lamp device 1 when said switch 5 is moved to its open circuit position connecting said lamp device 4 in series with said lamp device 1.

45 The electron emitting electrodes in both of said lamp devices 1 and 4 are of the indirectly heated type and consist of a heating element, such as a tungsten filament, in operative relation to a body of electron emitting material, such as barium oxide, when desired, or are of the type heated directly by the discharge and consist of a sintered mixture of metallic and oxide particles, when desired.

50 The two lamp devices 1 and 4 are mounted in adjacent positions to form a lamp unit which emits light in which the light rays from both of said lamp devices are commingled, when desired. When desired, the lamp device 1 is provided with a heat conservator, such as an evacuated envelope or a double walled jacket having the space between the walls thereof evacuated, to reduce the heat losses from said lamp device 1 and said lamp device 4 is likewise mounted in the same heat conservator to form a lamp unit.

55 A mercury vapor lamp of the high pressure, unsaturated vapor type is used in place of the lamp device 1, when desired. This type of lamp likewise requires an appreciable time after starting to attain its operating temperature. Such lamps comprise thermionic electrodes, a start-

ing gas and a limited quantity of mercury which is completely vaporized before said lamp has attained its operating temperature. A heat conservator is likewise useful for this type of lamp device.

5 While we have shown and described and have pointed out in the annexed claims certain novel features of the invention, it will be understood that various omissions, substitutions and changes in the forms and details of the device illustrated 10 and in its use and operation may be made by those skilled in the art without departing from the broad spirit and scope of the invention.

15 What we claim as new and desire to secure by Letters Patent of the United States is:—

1. An illuminating system comprising in combination two gaseous electric discharge lamp devices connected in series, one of said devices requiring a longer time to attain the operating temperature thereof than the other of said devices, means to short circuit said last named device until said first named device has attained its operating temperature and a high impedance connected in parallel with said last named device to maintain the discharge in said first named device during the starting period of said last named device.

2. An illuminating system comprising in combination two gaseous electric discharge lamp devices connected in series, one of said devices having a gaseous atmosphere therein comprising the vapor of a difficultly vaporizable material and requiring a longer time to attain the operating temperature thereof than the other of said devices, means to short circuit said last named device until said first named device has attained its operating temperature and a high impedance connected in parallel with said last named device to maintain the discharge in said first named device during the starting period of said last named device.

3. An illuminating system comprising in combination two gaseous electric discharge lamp devices connected in series, one of said devices having a gaseous atmosphere therein comprising so-45 dium vapor and requiring a longer time to attain the operating temperature thereof than the other of said devices, means to short circuit said last named device until said first named device has attained its operating temperature and a 50 high impedance connected in parallel with said last named device to maintain the discharge in said first named device during the starting period of said last named device.

4. An illuminating system comprising in com-55 bination two gaseous electric discharge lamp devices connected in series, one of said devices requiring a longer time to attain the operating temperature thereof than the other of said devices, means to short circuit said last named device until said first named device has attained its operating temperature and a high impedance connected in parallel with said last named device to maintain the discharge in said first named device during the starting period of said last 60 named device, said lamps being mounted in adjacent positions, the light rays from both said lamps being commingled.

WILLEM UYTERHOEVEN.
CORNELIS VERBURG.
